UNITED STATES PATENT OFFICE.

PIERRE JAMAIN, OF BORDEAUX, FRANCE, ASSIGNOR TO HIMSELF AND
JAMES M. TRIPPE, OF ORANGE, NEW JERSEY.

IMPROVEMENT IN CONSTRUCTING FIELD-FORTIFICATIONS.

Specification forming part of Letters Patent No. 10,213, dated October 6, 1863.

To all whom it may concern:

Be it known that I, PIERRE JAMAIN, of Bordeaux, in the Empire of France, have invented a new and useful Improvement in Field-Fortifications and other Earth-Works; and I do hereby declare that the following is a full, clear, and exact description of the same, reference being had to the accompanying drawings, forming part of this specification, in which—

Figure 1 is a vertical section of a casemated field-fortification constructed according to my invention. Fig. 2 is a perspective view of one of the hollow wooden voussoirs which constitute an important element of my invention. Fig. 3 is a longitudinal section of the voussoir in its folded up or portable condition. Fig. 4 is an end view corresponding with Fig. 3.

Similar letters of reference indicate corresponding parts in the several figures.

This invention consists in the employment, in the construction of field-fortifications and other military or engineering works, of light boxes of wood, or other suitable material, made in the form of voussoirs, and capable of being folded up to make them portable, so that each may be carried by a soldier behind his knapsack without inconvenience, or that they may be packed and carried in any other manner without occupying much room.

To enable others skilled in the art to make and use my invention, I will proceed to describe its construction and operation.

A, Fig. 1, are the boxes or hollow voussoirs, made of thin wooden boards or of sheet metal. These may be open on the side, which forms a portion of the interior of the arch, and are so represented. To form the arch these voussoirs or boxes are built over suitable centering-frames, B, as shown in Fig. 1, in the same manner as in building an arch of stone or other materials. When the arch has been built, the earth is piled upon it to any suitable depth, and the centering-frames removed.

To form a casemated field-fortification a trench is to be first dug of a width equal to the intended outside span of the arch, and of a depth about equal to the intended height of the arch, and of any length, and the hollow voussoirs or boxes are built up to form the arch on the bottom of this trench. The earth is then filled in to the trench and piled up in the arch in the form of an embankment of

any height sufficient to protect the arch from the enemy's projectiles.

At every place where a gun-port is required one or more of the voussoirs is omitted from the arch, as shown at r in Fig. 1, and an embrasure, s, is formed in the earth outside of this port, the top of the embrasure being formed by fascines t t or other means.

Figs. 2, 3, and 4 illustrate fully the construction of the boxes or hollow voussoirs to enable them to be folded up and carried by soldiers. I propose to make them either of wooden boards of about from three-eighths ($\frac{3}{8}$) to half ($\frac{1}{2}$) an inch thick, or of tin plate or other sheet-iron of a length of from eighteen (18) inches to two (2) feet, of a width across the face from twelve (12) to fourteen (14) inches, and of a depth from back to front of from five (5) to six (6) inches. The face-piece a is furnished with narrow ridged rims b b along its upper and lower edges, to which the top and bottom pieces, c c, are hinged by hinges d d in such a manner as to be capable of folding inward, as shown in Fig. 4. The end pieces, e e, are attached to the face-piece a by hinges h h, in such a manner as to fold within the top and bottom pieces, c c, close against the inner surface of the face-piece, as shown in Fig. 3, and a center supporting piece or brace, f, arranged between the top and bottom pieces, is hinged by hinges i to a cleat, g, which is secured across the inner surface of the face-piece a.

In folding up the box or voussoir the end pieces, e e, are first folded up, the piece f then folded over onto one of the pieces e, as shown in Fig. 3, and the side pieces folded one upon another over the piece f.

When the box or voussoir is required to be used, it is easily unfolded, and when unfolded is as well adapted to the purpose for which it is intended as though its parts were all rigidly secured together.

What I claim as my invention, and desire to secure by Letters Patent, is—

The employment, in the construction of field-fortifications and embankments, of portable voussoirs of wood, or other material, made to fold up, substantially as herein described.

PIERRE JAMAIN.
